UNITED STATES PATENT OFFICE.

ANKER PETERSEN, OF BOSTON, MASSACHUSETTS, ASSIGNEE TO BOSTON MACHINERY COMPANY, OF BOSTON, MASSACHUSETTS, A CORPORATION OF MASSACHUSETTS.

MACHINE FOR MAKING TUBULAR FABRIC.

1,072,984.

Specification of Letters Patent. Patented Sept. 9, 1913.

Application filed May 11, 1910. Serial No. 560,613.

To all whom it may concern:

Be it known that I, ANKER PETERSEN, a subject of the King of Denmark, residing at Boston, in the county of Suffolk and 5 State of Massachusetts, have invented new and useful Improvements in Machines for Making Tubular Fabric, of which the following is a specification.

This invention relates to improvement in 10 rotary braiding machines and the object of the invention is first to provide a rotary braiding machine having means for introducing into the fabric a higher number of strands of one series than there are in the 15 other, this object being attained by the use of a plurality of series of thread guides or thread directing members alternating with each other and means to reciprocate said thread guides of each of said series in a 20 direction opposite to that of the other, these guides being arranged in sets and the bobbin carriers supplying threads for the remaining series of strands being carried between the threads leading from each set of 25 thread guides or thread directing members. In this way the fabric is built up several times as fast as in machines employing only a single series of thread guides or thread directing members corresponding in number 30 to the individual spool or bobbin carriers.

Another object is to provide a stop motion which upon the breaking of any thread on the machine or upon the thread masses 35 becoming exhausted, shall operate to stop the driving mechanism of the machine.

I do not herein claim the novel features 40 of the spool carriers and their thread controlling devices, but reserve them for the subject matter of a separate application or applications.

The invention consists in the novel features of construction and in the combination and arrangement of parts set forth in the 45 following specification and particularly pointed out in the claims.

Referring to the drawings: Figure 1 is a plan of a braiding machine embodying my invention, some of the parts being broken away to disclose the mechanism to better advantage. Fig. 2 is an enlarged detail plan section of a portion of the machine. Fig. 3 is a sectional view taken on line 3—3 of Fig. 1. Fig. 4 is a plan section taken

on line 4—4 of Fig. 3. Fig. 5 is an enlarged detail side elevation of a portion of the machine. Fig. 6 is an enlarged detail plan section illustrating one pair of bobbins or spools and their corresponding pair of thread guides or thread directing members. Fig. 7 is a sectional view taken on line 7—7 of Fig. 2, illustrating the thread guides or thread directing members one up and one down and one of the spool or bobbin carriers and its bobbin passing between said guides. Fig. 8 is a detail sectional view taken on line 8—8 of Fig. 7, looking toward the right. Fig. 9 is a detail plan, partly in section, showing a modified form of spool or bobbin carrier. Fig. 10 is a diagrammatic view illustrating the parts and wiring of the electric stop motion.

Like numerals refer to like parts throughout the several views of the drawings.

In the drawings, referring particularly 75 to Figs. 3 and 4, 15 is the frame of the machine having mounted thereon a hollow stationary shaft 16 and having also supported thereon in suitable bearings a main driving shaft 17. On the shaft 17 is a clutch 18 comprising a member 19 loose on said shaft and a member 20 secured to said shaft, the former being shiftable into and out of engagement with the latter by means of a clutch shifting lever 21. The clutch members 19 and 20 are normally held in driving engagement by a pivoted latch 22 engaging a dog 23 pivoted on the lever 21. A helical extension spring 24 acts to withdraw the clutch member 19 from engagement with the clutch member 20 when the dog 23 is released from the latch 22.

Secured to the shaft 17 is a bevel gear 25 meshing with a bevel gear 26 secured to a shaft 27 journaled in suitable bearings 95 in the frame 15. Also secured to the shaft 27 is a spur gear 28 meshing with a spur gear 29, the latter being secured to a rotatable body 30 journaled on a sleeve 31 and said sleeve in turn being journaled on the hollow stationary shaft 16. A worm 32 secured to the shaft 17 meshes with a worm gear 33 secured to the sleeve 31. By the gearing just described, when the driving shaft is rotated in the proper direction, the gear 29 100 is rotated in the direction of the arrow α and the gear 33 in the direction of the arrow β , see Fig. 4.

Secured to the sleeve 31 is a body consisting of three parts, a wheel 34, a ring 35 and a ring 36 rigidly secured to each other by a series of posts 37, see Figs. 1, 2 and 5. The 5 wheel 34 and ring 35 are separated by a circumferential space 38 in which is located a series of spool or bobbin carriers 39 each of which is provided with an upwardly extending flange 40 located in a groove 41 provided in the ring 35 and a downwardly extending flange 42 located in a similar groove 43 provided in the wheel 34. Each of these carriers has thereon a spur gear segment 44, the teeth of which project toward the outside of the machine. Carried by the body 30 is a spur gear 45 with which a series of pinions 46 mesh, said pinions being, respectively, formed on or secured to a series of vertical shafts 47, the upper ends of which 10 are secured, respectively, to a series of pinions 48 arranged to mesh successively with the segmental gears 44. The shafts 47 are journaled at their upper ends in the ring 35 and at their lower ends in the ring 36 so that a relative rotative movement of the gear 45 and the body consisting of the parts 34, 35 and 36 results in the two series of pinions 46 and 48 being revolved about the axis of the gear 45 and being rotated about the 15 axes of their respective shafts 47, thus revolving the gear segments 44 about the axis of the gear 45, it being understood that the centers of the shafts 47 are so spaced that each gear segment in revolving passes into mesh with the next succeeding pinion 48 before passing out of mesh with the preceding pinion.

Each of the carriers 39 is provided with a radial spool or bobbin carrying pin 49 on which is mounted a suitable spool or bobbin 50, said pins being preferably slotted, as shown, so as to have a yielding frictional engagement with the bores of their respective spools. On each of the spools 50 a mass of thread 51 is wound in any usual or desired 40 manner and the thread 52 leading from the thread mass passes through an eye 53 of a rotating thread guide or slack controller 54 journaled concentric with the axis of the thread mass on a hollow thread guide 55 secured to a U-shaped frame 56 carried by each spool carrier 39. Adjacent to the inner end of each thread guide 55 is a second thread guide 57 separated therefrom by a 45 slight space, as shown in Figs. 2 and 7, the purpose of this being explained hereinafter. It will be understood that the various threads 52 lead through the guides 55 and 57 to the center of the machine, that is, to the braiding point. As the thread is drawn from 50 each thread mass the tension thereon causes the thread guide or slack controller 54 to be rotated by the thread as it unwinds from the thread mass in an obvious manner, it being understood that said slack controller

permits the thread to be drawn from the thread mass without tangling and with the least amount of resistance.

Supported on the ring 36 is a series of posts 58 and on each of these posts is supported a pair of levers 59 and 60 constituting movable thread guides or thread directing members, the levers 59 being the members of one series and the levers 60 being the members of a second series, which alternate with each other about the machine. 70 To each lever 59 is pivotally connected a link 61 and to each lever 60 is pivotally connected a corresponding link 62. A series of circumferentially arranged levers 63 pivotally mounted substantially midway of their length on the ring 36 have journaled thereon, respectively, cam rolls 64 located in the groove of a sinuous cam 65 carried by the body 30. A series of similar levers 66 located at a higher level pivotally mounted on the ring 36 have mounted thereon, respectively, cam rolls 67 located in the groove of a sinuous cam 68 also carried by the rotary body 30. Opposite ends, respectively, 80 of each lever 63 are pivotally connected to links 61 and 62 and the next succeeding links 61 and 62 are pivotally connected to opposite ends, respectively, of the next succeeding lever 66 and so on around the machine, 85 the arrangement being such that when a relative rotation is imparted to the ring 36 and the cams 65 and 68, the two series of levers 59 and 60 are simultaneously reciprocated in opposite directions, that is, when 90 one entire series 59 is lowered, the entire series 60 is raised, as shown in Fig. 7, at which time the spool carriers pass therebetween. As the levers 59 and 60 are preferably exceedingly light and delicate in construction, I provide guides 69, 70 and 71, 95 see Figs. 2, 5 and 7, preventing lateral movement thereof.

Secured to the ring 36 is a series of brackets 72 located at intervals therearound, each of these brackets constituting a support for two spools or bobbins 73 and 74 journaled, respectively, on upright pins 75 and 76. From the mass of thread on each spool or bobbin 73, a thread 77 leads through a thread guide 78 having a vertical slot 79 therein, said guide and also the pivot of the levers 59 110 thread guided by the thread guides 81 thence across a pin 82 constituting a thread guided and also the pivot of the levers 59 115 and 60, said thread passing thence through an eye 83 provided in the movable thread guide or thread directing member 59 and leading therefrom to the braiding point at the center of the machine. Similarly, a 120 thread 84 leading from the thread mass on the spool or bobbin 74 passes through the slots 79 in the thread guide 78, thence through a thread guide 85, thence upwardly through a thread guide 86, thence across the 125

pin 82 and through an eye 87 provided in the movable thread guide or thread directing member 60 from whence said thread passes to the braiding point at the center of the machine.

The thread guides 81 and 86 are yieldingly mounted on the bracket 72 and are of such strength that the tension upon the threads normally retains said guides in their innermost position, that is, in the position shown in Fig. 2, and in full lines in Fig. 7. If the thread guided by the thread guides 81 and 86 breaks, said guides fly back from the position shown in full lines in Fig. 7 to the position shown in dotted lines therein, being limited in their movement by a plate 88, the purpose of this construction being hereinafter fully set forth.

In order to maintain a proper tension on the threads 77 and 84, I provide suitable tension devices 89 and 90 acting on the thread masses on the spools 73 and 74, said tension devices being secured, respectively, to yielding journaled supports 91 and 92 having secured thereto, respectively, arms 93 and 94. These tension devices form the subject matter of U. S. Letters Patent No. 931,084, issued to me August 17, 1909, to which reference may be had for details of construction. Vertical rock shafts 95 and 96 are provided, respectively, with arms 97 and 98 which are normally held in contact with the thread masses on the spools 73 and 74, respectively, by helical torsional springs 99 and 100. Secured to the rock shaft 95 is an arm 101 which by rocking movement of the shaft 95 may be carried into engagement with the arm 93 to move the tension devices 89 out of engagement with the spool 73 of the thread mass thereon so as to enable the operator to place a fresh spool of thread on the pin 75. For convenience in manipulating the rock shaft 95, the same is provided with an arm 102 which also serves another purpose hereinafter described. In like manner, the rock shaft 96 has secured thereto an arm 103 adapted to engage the arm 94, said rock shaft being also provided with an arm 104 similar to the arm 102.

I will now proceed to describe the construction of the stop motion by means of which the machine is stopped upon the breaking of one or more of the three series of threads 52, 77 and 84 and also upon the thread masses on the spools 73 and 74 becoming nearly exhausted.

The plate 88 which constitutes the stop for the yieldable thread guides 81 and 86 constitutes also a contact plate suitably insulated from the post 58 on which it is mounted. Each contact plate 88, see Fig. 10, is connected by a wire 105 to a wire 106 extending around and supported on the ring 26, the latter wire being connected to one of the series of segmental contact plates 107

mounted upon and insulated from the ring 35, as shown in Fig. 7. The plates 107 are electrically connected to each other in a continuous series by means of wires 108, as shown in diagram in Fig. 10, and these wires 70 will in practice be made in the form of U-shaped connections extending up and across each pair of levers 59 and 60 so that the contact plates 107 together with the wire connections 108 constitute in effect a continuous 75 conductor and yet said contact plates are placed low enough to contact with a series of brushes 109 supported on and insulated from the spool carriers 39, respectively.

Supported on each of the spool carriers 39 is a movable contact arm 110 adapted to be moved into and out of contact with the brush 109 supported on said spool carrier, said arm being formed on or secured to a rock shaft 111, there being provided a helical torsional spring 112 normally tending to carry the arm 110 into contact with the brush 109. Such contact, however, is normally prevented by an arm 113 formed on or secured to the rock shaft 111 and bearing 98 on the thread 52 between the thread guide 55 and the thread guide 57, as shown in Figs. 2 and 7, said thread guides being placed thus close together so as to prevent the thread from normally yielding under the influence 95 of the spring-pressed arm 113 resting thereon. If, however, the thread 52 should break thus releasing the arm 113, the spring 112 will, of course, carry the contact arm 110 into contact with the brush 109. The contact 100 arms 110 are electrically connected to the carriers 39 and are thus grounded upon the frame of the machine, as indicated diagrammatically in Fig. 10.

One of the contact plates 107 is connected 105 by a wire 114, see Figs. 2 and 10, to a central plate 115, see also Fig. 3, said plate being secured to and insulated from the hub of the wheel 34 and resting upon a metallic bushing 116 supported in a recess in the upper end of the hollow stationary shaft 16 and insulated therefrom, see Fig. 3. The bushing 116 is connected by a wire 117 passing downwardly through the hollow shaft 16 to a suitable source of current, such as a 115 battery 118. Thus through the contact of the rotating plate 115 on the stationary plate 116, the moving contact plates 107 are always in electrical connection with the battery 118.

Returning now to the contact plates 88, it will be evident that if one of the threads 77 should break, its respective yieldable guide 80 will fly back into contact with its contact plate 88, and in like manner, if one of the 125 threads 84 should break, its respective yieldable guide 86 will fly back into contact with the plate 88, as shown in Fig. 6. Each of the arms 97 and 98 is made of such length that when the thread mass against which it 130

respectively bears becomes diminished to a certain size, said arm will be rotated under the influence of its controlling spring past the periphery of the thread mass. In Fig. 5 6, the arm 97 is shown as having moved under such conditions, thus carrying the arm 102 into contact with the contact plate 88.

Referring now to Figs. 4 and 10, the pivoted latch 22 constitutes an armature adapted to coöperate with an electro-magnet 119, one end of the winding of which is connected by a wire 120 to the positive terminal of the battery 118 and the other end of 15 which is connected by a wire 121 to a contact plate 122 against which the clutch shifting lever 21 normally rests, said lever being grounded on the frame of the machine. Normally, the stop motion circuit is open, 20 but if through the breaking of one or more of the threads 77, one or more of the yieldable thread guides 81 contact with their respective contact plates 88 a circuit is completed through the wires 105, 106, contact plates 107, wires 108, 114, plate 115, bushing 116, wire 117, through the battery 118, wire 120, electro-magnet 119, wire 121, contact plate 122 and clutch shifting lever 21 to the ground, that is, to the frame of the 25 machine, thus causing the electro-magnet 119 to become energized. The energizing of the electro-magnet lifts the latch 22 thus releasing the dog 23 and allowing the clutch member 19 to be carried out of engagement with the clutch member 20 under the influence of 30 the spring 24. In like manner, if one or more of the threads 84 should break, the thread guide or guides 86 released thereby would operate to stop the machine. Also 35 since the arms 102 and 104 are grounded upon the frame of the machine, it will be evident that if one of the thread masses on the spools 73 and 74 should become exhausted a circuit will also be completed to 40 the electro-magnet thus acting to stop the machine. So also if one of the threads 52 should break, a circuit would be completed to the electro-magnet. If in any of these cases the electro-magnet is energized and 45 the clutch shifting lever 21 is thereby released, said lever in passing out of contact with the plate 122 breaks the circuit at that point.

In Fig. 9, I have shown a modified form 50 of spool carrier which differs from that hereinbefore described in that there is provided a rotary thread guide or slack controller 123 journaled on a plug 124 fitted into the end of the spool and having expandable springs 125 engaging the bore of the spool to hold the same in place therein. The thread passes through an eye 126 provided in the thread guide or slack controller 123 and thence across two stationary thread 55 guides 127 and 128 to the braiding point at

the center of the machine, said slack controller acting to prevent the thread from tangling as it is drawn from the thread mass. In this case, there are two fingers 129 and 130 bearing against the thread, the finger 130 being located between the guides 127 and 128 and the finger 129 being located between the guide 127 and the end of the carrier, as clearly shown, the ends of the guides being turned upwardly and the ends of the fingers being turned downwardly to prevent the thread escaping therefrom.

Having thus described my invention, what I claim and desire by Letters Patent to secure is:

1. A machine for making tubular fabric having, in combination, a series of spool carriers arranged about an axis, two series of thread guides arranged about said axis in sets, the guides of each set being located adjacent to each other, means to reciprocate one of the guides of one of said sets simultaneously with one of the guides of the succeeding set in opposite directions longitudinally of said axis, and means to progress said spool carriers relatively to said thread guides.

2. A machine for making tubular fabric having, in combination, a series of spool carriers arranged about an axis, two series of thread guides arranged about said axis in sets, the guides of each set being located adjacent to each other, means to reciprocate one of the guides of one of said sets simultaneously with the adjacent guide in the succeeding set in opposite directions longitudinally of said axis, and means to progress said spool carriers relatively to said thread guides.

3. A machine for making tubular fabric having, in combination, a series of spool carriers arranged about an axis, a plurality of series of radiating levers constituting thread guides alternating with each other about said axis, a plurality of cam levers pivoted substantially midway of their lengths, means connecting opposite ends of each of said cam levers with one of the levers constituting said thread guides, respectively, cams to rock said cam levers upon their pivots simultaneously in the same direction to reciprocate said thread guides connected at opposite ends thereof in opposite directions longitudinally of said axis, and means to progress said spool carriers relatively to said thread guides about said axis.

4. A machine for making tubular fabric having, in combination, a series of spool carriers arranged about an axis, a plurality of series of thread guides alternating with each other about said axis, two sinuous cams, a set of cam levers pivoted substantially midway of their lengths for each of said cams, the cam levers for one of said

cams alternating with the cam levers for the other of said cams, operative connections between one end of each of said cam levers and one of the thread guides of 5 one of said series respectively, and between the opposite ends of each of said levers and one of the thread guides of the other of said series respectively, and means to relatively revolve said cams and said thread guides 10 thereby to reciprocate said thread guides of each of said series longitudinally of said axis in a direction opposite that of the other.

5. A machine for making tubular fabric having, in combination, a series of spool carriers arranged about an axis, two series 15 of levers constituting thread guides alternating with each other about said axis and arranged in sets, the guides of each set being located adjacent to each other, two series of cam levers alternating with each other about said axis, two sinuous cams each adapted to actuate the levers on one of said series of cam levers respectively, operative means connecting one end of each of said 20 cam levers with one of the levers constituting the thread guides of one of said sets, operative means connecting the opposite ends of said cam levers with the adjacent levers constituting the thread guides of 25 the succeeding sets of levers, means to 30

relatively revolve said cams and said thread guides thereby to reciprocate the thread guides of each of said series longitudinally of said axis in a direction opposite to that of the other. 35

6. A machine for making tubular fabric having, in combination, a series of spool carriers arranged about an axis, a plurality of series of radiating levers constituting thread guides alternating with each other 40 about said axis, a plurality of circumferentially arranged cam levers pivoted substantially midway of their lengths, means connecting opposite ends of each of said cam levers with one of the levers constituting 45 said thread guides respectively, cams to rock said cam levers upon their pivots simultaneously in the same direction to reciprocate said thread guides connected at opposite ends thereof in opposite directions longitudinally of said axis, and means to progress said spool carriers relatively to said 50 thread guides about said axis.

In testimony whereof I have hereunto set my hand in presence of two subscribing 55 witnesses.

ANKER PETERSEN.
